UNITED STATES PATENT OFFICE.

WILLIAM F. GATEWOOD, OF DECATUR, ILLINOIS, ASSIGNOR TO THE F. B. TAIT MANUFACTURING COMPANY, OF SAME PLACE.

END-GATE FOR WAGON-BEDS.

SPECIFICATION forming part of Letters Patent No. 634,555, dated October 10, 1899.

Application filed April 17, 1899. Serial No. 713,310. (No model.)

To all whom it may concern:

Be it known that I, WILLIAM F. GATEWOOD, of Decatur, in the county of Macon and State of Illinois, have invented certain new and useful Improvements in End-Gates for Wagon-Beds, of which the following is a specification.

This invention is designed to provide an end-gate that may be used as a scoop-board and that will also permit the contents of the bed to be discharged by dumping. It is exemplified in the structure hereinafter described and it is defined in the appended claims.

15 In the drawings forming part of this specification, Figure 1 is a perspective representation of my end-gate in position to be used as a scoop-board. Fig. 2 is a side elevation showing the end-gate locked against the end 20 of the bed. Fig. 3 is a detail in plan. Fig. 4 is a side elevation showing how the fastenings of the end-gate are manipulated preparatory to dumping. Fig. 5 is a side elevation illustrating the action of the end-gate 25 when the bed is dumped to discharge its load from the rear end.

The wagon-bed is shown at 1. At 2 is shown one of a pair of slide-plates that fit over the upper edges of the lowest side-boards of the 30 wagon-bed and bear against the cleats at the end of the bed. Pins 3 project sidewise from the slide-plates and form pivotal bearings for links 4, which aid in supporting the end-gate.

The end-gate is in the form of an ordinary 35 scoop-board; and it consists of the board 6^a, which forms the end-gate, and the scoop-board and the side plates 6, which are fastened to the board 6^a and embrace the end of the bed when the gate is closed. Each side 40 plate has a strip 7 at its lower inner corner, and such strips are bent outward at 8 to form stops to support the end-gate when it is used as a scoop-board, as shown in Fig. 1. Links 4 are hinged one to each side of the bed, and 45 they connect pivotally with the lower outer corners of the side plates of the gate at 5. The upper ends of links 4 extend above pivot-pins 3 and are projected forward along the bed, as shown at 4^a. The forward-projected parts of the links are turned with their

widths horizontal, and a set of vertical holes are formed through the horizontal extensions, as shown in Fig. 1. Hooked links 9 are connected pivotally at 10, one on each side of the end-gate, and eyes 11, fastened to the bed, 55 provide for engagement of the hooks of the links. The hooked links are so pivoted on the end-gate that their hooks may be made to engage the holes in the horizontal extensions 4^a of links 4, as shown in Fig. 2, thus locking 60 the end-gate against the end of the bed, and may also be made to engage eyes 11, as shown in Fig. 4, preparatory to dumping the contents of the bed.

The slide-plates 2 are preferably provided 65 on their inner faces with adjustable slides 13, which have bearings 15, adapted to bear against cleats 12 near the end of the bed. The slides are slotted, as shown at 14 in Fig. 1, and the plates have bolts 16, by means of 70 which the slides are held in position. A slide is shown in detail in Fig. 3. In connecting the end-gate with the bed the slide-plates 2 are set over the edges of the bed proper, and the slides 13 are adjusted until the pins 3 are 75 in proper position to hold the end-gate tightly against the bed when the links are in the positions shown in Fig. 2. Afterward the side-boards of the bed are put in place. The links 9 hold the upper end of the gate firmly against 80 the bed by direct pull, and they also hold the lower end against the bed by indirect action through links 4. The outward pull of links 9 tend to pull the upward extensions of links 4 outward and so force the lower ends inward or 85 toward the bed. When the hooked links are loosened, the end-gate may be swung downward on pivots 5 until stops 8 engage links 4, as shown in Fig. 1, when the gate may be used for a scoop-board. Preparatory to dumping 90 the contents of the wagon out of the rear end thereof the hooked links are disconnected from the extensions 4^a of links 4 and engaged with eyes 11. Then when the bed is dumped, as shown in Fig. 1, the end-gate will swing 95 rearward and upward on pins 3 and eyes 11 and provide a passage-way for the contents of the bed. The set of holes in horizontal extensions 4^a permit considerable adjustment of plates 2 without getting the horizontal ex- 100

tensions out of reach of the hooked links, and this facilitates the attachment of the gate to beds having cleats 12 of unusual width or unusually placed. To accommodate beds of 5 different height, different holes for pins 3 may be made in links 4, as shown in the drawings.

What I claim is—

1. The combination, with a wagon-bed, of 10 a pair of pivot-pins attached one to each side of the bed near the rear end and above the bottom thereof, a second pair of pivot-pins attached to the bed one above each of the primary pivot-pins, an end-gate closable 15 against the end of the wagon-bed, a pair of links connected pivotally with the lower corners of the gate and the primary pivot-pins and extended upward and forward to the primary pivot-pins and a second pair of links connected pivotally with the end-gate above the primary links 20 and below the secondary pivot-pins, when the gate is closed, and attachable to the secondary pivot-pins when the gate is closed and the said secondary links are extended approximately parallel with the primary links; where- 25 by the upper end of the gate may be held from opening and the lower end of the gate may swing upward and away from the bed.

2. The combination, with a wagon-bed, of 30 a pair of pivot-pins attached one to each side of the bed near the rear end and above the bottom thereof, a second pair of pivot-pins attached to the bed one above each of the primary pivot-pins, an end-gate closable 35 against the end of the wagon-bed, a pair of links connected pivotally with the lower corners of the gate and extended obliquely upward and forward to the primary pivot-pins and a second pair of links connected pivotally with the end-gate above the primary 40 links and below the secondary pivot-pins, when the gate is closed, and attachable to either the secondary pivot-pins or to the up-

per ends of the primary links, substantially as specified.

3. The combination, with a wagon-bed, of 45 a pair of pivot-pins attached one to each side of the bed near the rear end and above the bottom thereof, a second pair of pivot-pins attached to the bed one above each of the primary pivot-pins, an end-gate closable 50 against the wagon-bed, a pair of links connected pivotally with the lower corners of the gate and the primary pivot-pins and extended above such pivot-pins, and a second pair of links connected pivotally with the end-gate 55 above the primary links and below the secondary pivot-pins, when the gate is closed, and attachable to either the secondary pivot-pins or the upper extensions of the primary links, substantially as specified. 60

4. The combination with an end-gate for wagon-beds, of a pair of pivot-pins attachable to the sides of a wagon-bed, a pair of links pivotally connected with the lower corners of the gate and with the pivot-pins and extended 65 above the pivot-pins, and a second pair of links connected with the gate between the ends thereof and connectable with the upper extensions of the primary links when the gate is closed, substantially as described. 70

5. The combination with an end-gate having side wings, or plates, of a pair of links pivotally connected with the lower corners of the gate and with the sides of the bed above the bottom thereof, and stops projecting from the 75 lower ends of the side plates to engage the swingable links when the gate is lowered, substantially as described.

In testimony whereof I sign my name in the presence of two subscribing witnesses.

WM. F. GATEWOOD.
